VENDING MACHINES

Reginald Hugh Fred Carter, Littlehampton, England, assignor to X-O-Matics (Sales) Limited, London, England

Filed Apr. 25, 1961, Ser. No. 105,452

Claims priority, application Great Britain Apr. 27, 1960
12 Claims. (Cl. 312—97.1)

The present invention relates to vending or dispensing machines (hereinafter called vending machines) and especially those which are operative after insertion of a coin. These machines may be used for vending articles of food, e.g., eggs, vegetables, fruit or other goods whether packed or not.

It is an object of the invention to provide a vending machine which is simple in construction and cheap to make and accordingly the machine according to the present invention comprises a holder for the goods to be sold having a number of compartments or platforms (hereinafter and in the claims called compartments) arranged in a helical formation, the holder being supported to move in a helical path to bring each compartment in turn into register with a closable opening, and comprising means operative when a coin is in a position to serve as a link or coupling element to unlock or unlock and open a closure member for said opening and allow the holder to advance to bring another compartment or platform to the opening.

Although, as hereinafter described, the holder may be associated with means for lifting and turning it, e.g., from a lower refrigerating chamber, a very simple form of the machine is one constructed so that the holder can turn and descend by gravity under the control of a helix or part helix and so that under the control of appropriate indexing mechanism on the casing of the machine, operated through the medium of a pivoted closure member, with every descent and turn of the holder with each indexing operation a new compartment containing goods to be vended will be brought to the opening and an empty compartment moved on.

Such a machine requires no driving motor or like source of power. The various compartments can be successively charged and the holder raised to a position from which, whenever a coin has been inserted and the indexing mechanism operated through the medium of the closure member, the holder will descend and turn through a sufficient angular extent to remove one empty compartment from the closure member opening and bring the next charged compartment into the position previously occupied by the empty one now advanced.

To simplify the manufacture of the machine it is preferred to provide either a fixed support for the holder or the holder itself with a series of pins spaced on a helix and to provide the holder or the support as the case may be with a continuous helical surface which may be a local surface extending over only one convolution or less where the holder makes several convolutions in its complete travel and thus the need for forming long continuous helical surfaces and the consequent difficulties of machining are obviated. It is preferred to secure the said continuous surface to the holder, e.g., by making the said surface the under edge of a bearing sleeve seating on a number of the pins which may be arranged to project radially from a central column in helical disposition, the holder being rotatable and movable up and down with respect to the said column.

The closure member may be a fold down flap or gate. It may comprise a window through which the contents of a compartment can be seen.

2

The machine specifically described herein comprises a fold-down closure member which will be normally closed and locked and operates so that the insertion of a coin into an appropriate slot, followed by the manipulation 5 of an operating control, leads to the opening or unlocking of the said member, and whilst the closure member is open, the holder is locked in position so that it cannot be advanced to a subsequent station to allow improper access to be had to any of the other goods in the machine and 10 with the closing of the closure member after goods have been removed from the relative compartment, the holder is only allowed to turn and descend to bring a new charged compartment to the delivery opening when the closure member has been so closed and retained as not to be capable of being opened improperly, i.e., until another coin has been inserted.

This machine comprises a coin track means, means to support a coin in a predetermined position, control means operable from the exterior of the machine for 20 displacing a locking bolt which co-operates with the closure member, the arrangement being such that the coin when in such position will transmit motion from the said control means to the bolt to release the closure member, the transmission of such motion being prevented 25 when a coin is not in position.

The holder may comprise vertical members which together form a rack and the indexing means comprise a spring loaded catch or pawl normally released from the said rack, said closure member having stop means which 30 co-operate, when the closure member is closed, with the said rack to register a compartment with the said opening. The vertical members may be the outer vertical edges or rods of the compartment walls.

The indexing means may comprise means responsive to 35 the initial opening of the closure member to cause the said pawl or catch to move into position to co-operate with the rack and further opening of the closure member to release said stop means from the rack so that the holder can turn a small angular extent to engage the pawl or catch and bring the rack into a position in which the holder, when next released by the pawl or catch can turn until the next vertical member of the rack is held by the stop means of the then closed closure member.

Spring-operated means may be provided responsive to 40 the release of the bolt from the closure member which cause an initial opening of the latter sufficient to bring the pawl or catch into operative position.

The initial opening of the closure member may be 45 limited by a cam on the closure member co-operating with lever means co-operating with the locking bolt to prevent premature return of the bolt and so that the further opening of the closure member further displaces the bolt.

The locking bolt may be provided with means for positively displacing a coin for release down a track if the coin should tend to remain after the closure member has been released and to hold a second coin, if one be inserted while a preceding coin is in operative position, from prematurely falling down the track.

Means may be provided whereby the operation of the pawl or catch to release the holder for rotation occurs only 50 by final closure movement of the closure member when the locking bolt has been again caught with the closure member and retains the closure member against improper opening.

Preferably the holder is within a casing comprising a door which can be normally locked or opened for charging the holder and the said opening is in the said door and the closure member is pivoted to the door in the lower region thereof.

The locking pawl or catch may be a lever which is fulcrumed to the casing and co-operating structure of the indexing means may be carried by the door, the said lever and the said other structure being brought into operative relation by the closing of the door to release the pawl or catch from the rack, the pawl or catch serving to control the operative feed of the holder and yielding ratchet fashion and permitting step-by-step operation of the holder when the holder is turned in the opposite direction during charring of the latter with the door open.

The pawl or catch lever may co-operate with an intermediate lever also fulcrumed to the casing, e.g., to a bracket thereon, and the said other structure comprise a master lever fulcrumed to the door and which is brought into cam-co-operation with the said intermediate lever by the closing of the door.

The master lever may be spring-biased and act (a) partially to open the closure member when the locking bolt has been withdrawn and (b) cause the pawl or catch to move in the path of the rack, and lever means may be provided on the door co-operative with a cam on the closure member and with the locking bolt so that further opening of the closure member further displaces the locking bolt away from the bolt of the closure member against a spring return means and also withdraws the stop means on the closure member from the rack to permit the holder to turn through a small angular extent until brought to a stop by the pawl or catch, the closing of the closure member operating to release the locking bolt for movement into co-operation with the closure member, to bring said stop means carried by the closure member again into the path of the rack and to release the pawl or catch to permit turning of the holder only when the closure member has been sufficiently closed and locked by the locking bolt that it cannot be improperly opened and access had to goods in the holder.

When with the door and the closure member closed, a coin is inserted and the control means operated to release the locking bolt from the closure member, a cranked end of the master lever, remote from that end co-operating with the intermediate lever, may be caused by spring-bias of the master lever, to act and follow behind a lower extension of the closure member below its fulcrum, the spring biassing the pawl or catch then operating to turn the pawl or catch into the path of the appropriate rack member of the holder and also to hold the intermediate lever to position its cam end to be engaged by the co-operating end of the master lever at a latter stage.

The holder will previously, i.e., with the closure member closed, have been held against rotation, not by the pawl or catch but by the aforesaid stop on the closure member itself co-operating with another vertical rack member on the holder so that when the closure member is opened the latter stop becomes inoperative and allows the holder to move round by a small amount, the pawl or catch being then located so as to operate to secure the holder against further rotation when the holder has cleared the said stop.

When goods have been removed from the compartment and the closure member reaches the final stage of its closing movement the said lower extension thereof presses against the master lever which by virtue of its cam co-operation with the corresponding end of the intermediate lever causes the latter to turn the pawl or catch lever against the spring urge of the latter to release the pawl or catch from the path of movement of the holder and allow the holder to descend and turn so that the empty compartment will move on and the new compartment come into registration with the opening, being stopped at that position by the stop on the closure member itself, but the said release takes place during the final closing of the closure member when the coin-controlled locking bolt has moved into position to prevent re-opening of the closure member before a further coin is inserted.

Provision may be made whereby when the last com-

partment has been exposed in the opening an indicator is operated showing that the holder is empty.

One embodiment according to the invention will now be described more particularly.

With reference to the accompany diagrammatic drawings in which FIG. 1 is a front view of the open cabinet, FIG. 2 is a sectional plan, FIG. 2a a fragmentary part thereof in another position, FIGS. 3 4 and 5 are views of the locking and indexing mechanism.

FIGS. 6 to 11 illustrate a modified machine, FIG. 6 showing this machine with the door open to expose the holder in the cabinet and the mechanism carried by the door. FIG. 7 is a part sectional plan showing the pawl of the indexing mechanism carried by the cabinet. FIG. 8 is a detail view of a locking device for the closure member. FIG. 9 is a detail view of the locking bolt mechanism; FIG. 10 is a front elevation and FIG. 10a a side view of an "Empty" indicator and FIG. 11 is a view of the coin insertion mechanism.

The machine illustrated in FIGS. 1 to 5 comprises a casing including cabinet 1, e.g., of rectangular horizontal cross-section having a circular-section column 2 extending vertically centrally thereof. This column is provided with a series of radially outwardly projecting pins 3 arranged on a helix. The column is fitted in a top flange or bearing sleeve 2a and can be locked by setscrews 2b when the storage holder 4 registers with the flap herein-after described.

The storage holder 4 for the goods is provided with multiple goods-supporting platforms 5 arranged on a helix and forming the bottoms of compartments formed by a cage or other arrangement. The holder has an upper bearing sleeve 6 formed with a helical lower edge 7 whereby the holder can be supported through the medium of the said pins.

The helical edge aforesaid may be one or a part of one convolution and engage say three of the pins only at any position. The holder is rotatably supported and can only turn about the axis of the column and rise and fall.

The storage holder can descend and turn under the control of the helical arrangement in steps as determined by the indexing means hereinafter described and when discharged can be turned back and lifted and held in the upper position.

There may be any convenient number of compartments 8 say six for every complete turn and enough compartments to permit of several complete turns.

The compartments are formed by the platforms 5 aforesaid (which may be of grid or open structure) and radial divisions 10 (which may also be of wire of open form) terminating in vertical outer edges, which may be formed by vertical rods or strips 11 together forming a rack. The indexing means co-operate with these rods as will be later described.

The cabinet has a front door 9 hinged about a vertical axis 12 at one side of the cabinet.

Mounted on a bracket 13 on the hinge side of the interior of the cabinet is a pawl or catch lever 14 which is medially fulcrumed at 15 and has the pawl end 16 at the end of one arm, the arm extending furthest into the cabinet from the front thereof, and the end of the other (tail) arm 17 is arranged to co-operate with another medially fulcrumed lever 18 also mounted on the said bracket and herein called the intermediate lever. The pawl-locking lever is spring-loaded at 19 so as to be held in locking position co-operating with one of the said vertical rods of the holder when the spring-load takes control and the holder is to be prevented by the pawl-locking lever from turning (FIG. 2). The intermediate lever and the said tail arm of the pawl-locking lever co-operate so that when the intermediate lever is turned in one direction the pawl-locking lever will be moved against its spring to release the holder for turning (FIG. 2a).

Mounted on the inside of the door is the aforesaid

master lever 20. This has one arm 21 the free end of which co-operates with the end of the intermediate lever 18 remote from the pawl or catch lever, these ends being adapted to co-operate cam-fashion. The master lever has another (tail) arm 22 which may be situate at a lower level than said first arm, e.g., the said arms being spaced on a central pivot or bearing member. The angle between the arms 21 and 22 of the master lever 20 may be adjusted by loosening the connecting nut 20a to vary the amount by which the arm 21 displaces the intermediate lever 18 and hence the pawl 14 as hereinafter described.

The door has an opening adapted to register with one compartment at a time and this opening is normally closed by a flap closure member 27 pivoted about a lower horizontal axis 27b and having depending offset or cranked inward extension 27a. The master lever is spring loaded at 28 so that its tail arm aforesaid engages the said inward extension and will urge the flap to partially open position when the flap is released as later explained.

The flap is provided with an external fixed handle 29 provided with a locking pin 30 which extends into the interior of the cabinet with the door and the flap both closed. The said pin has a peripheral groove 31 for co-operating with a locking bolt 32 as later described. At the side of the said flap which will be remote from the hinge axis of the door when the door is closed, a stop 33 projects inwards from the flap and is fixed to or is an integral part of the flap. At the other side of the flap an inward projection is provided which forms an edge cam 34. The aforesaid locking bolt is slidably mounted on the door adjacent the inside of the flap, one end of the bolt engaging the said groove of the pin of the flap and holding the flap closed until the bolt is released. This locking bolt is contained and guided by a bracket 32a mounted on the door 9 and is spring-loaded (35) in such manner that the spring tends to hold the bolt in locking position.

A coin receiving mechanism is provided on the door with a suitable coin-receiver and chute 36 to allow a coin of given denomination to fall into a position in which the coin can control the indexing means.

The coin when dropped through the chute will come to rest on two pins 37 between an angular end plate 38 apertured at 38a of the locking bolt and fixed plate 39 apertured at 39a, apertures 38a and 39a being in line. The said pins 37 are carried by the fixed plate 39 and abut the plate 38 of the locking bolt when this is in the position shown in FIG. 4. A spring-loaded lever 40 (which we term the purchaser's lever) is arranged on the inside of the door and has an external handle 41. The purchaser's lever has a pin end 42 which can pass through said apertures 38a and 39a and have no action on the locking bar in the absence of a coin. When however a coin 43 has fallen through the chute onto the said support pins, the pin end of the said purchaser's lever will pass through the aperture 39a and thrust on the coin so that this transmits motion to the plate 38 carried by the locking bolt and releases the locking bolt from its groove in the said pin and takes the coin off the pins secured to the plate 39 to enable this to drop when the purchaser's lever is released, the closure member having meanwhile sprung partially open as later described. The locking bolt has a horizontal inwardly extending plate 44 one face of which will lie normally adjacent one face of the coin, just permitting the coin to position itself at rest edge-on its pin supports.

An L-shaped lever 45 pivoted (46) at its angle to the door or a bracket thereon has a short arm 47 the end of which co-operates with the said edge cam 34 on the flap and a long arm 48 the end of which co-operates between stops on the locking bolt. When the closure member springs partially open as aforesaid the edge cam 34 on the closure member will co-operate with the arm 47 of the lever 45 to prevent immediate further opening of the closure member as is hereinafter more fully described

and also to prevent retraction of the bolt 32 and plate 38 to ensure that the coin is not carried back onto the pins 37 when the purchaser's lever is released.

The locking bolt is slidable in guides adjacent the inside of the door.

The apparatus operates as follows:

The holder will be loaded in stages after reaching its lowest position and when its contents have been vended. At each stage a suitable number of compartments will be charged and after each stage the holder will be turned in a direction opposite to that in which it turns for vending, say anticlockwise. The door will then be open and the master lever 20 out of operation, and the spring-loaded pawl-locking lever 14 is then urged by its spring 19 into the path of the periphery of the holder and is shaped so that the holder can be turned and raised through a requisite angular extent and ride past the pawl end 16 ratchet fashion but will be held by the pawl spring-urged into locking position against undesired reverse rotation when the holder is to be held stationary under its own weight.

After fully charging and raising the holder, the door will be closed and locked and the flap closed. One of the said vertical rods 11 will then be urged under the weight of the holder against the said stop 33 on the flap and the pawl-locking lever 14 will be freed from the holder (FIG. 2a). A charged lower compartment will then be registered with the flap-closed opening in the door.

30 The purchaser will now insert a coin 43 into the coin slot and this will fall down the chute on the inside of the door and between the end angle plate 38 of the locking bar 32 and the fixed plate 39 carrying the support pin or pins 37 and the coin will come to rest on the pins 35 so that the pin-end 42 of the spring-loaded purchaser's lever 40 when this is operated will thrust on the coin and transmit motion to the locking bolt 32 to release the engagement of the said bolt with its groove in the pin 30.

35 The spring 28 of the master lever 20 will then cause 40 the tail arm 22 of the latter to open the flap through a certain angular extent, say 10-30° until the L-lever 45 working with the cam 34 on the flap prevents the flap from immediate further opening. The opening of the flap will release the master lever 20 from the intermediate lever 18 and the pawl-locking lever 14 will spring into locking position (FIG. 2). The purchaser can then further open the flap and displace the L-lever 45 by the said cam and further displace the locking bar 32, ensuring that the coin will be released if it has not already been released.

45 When the goods from the relevant compartment have been extracted, the flap is then closed. During the closing movement, the L-lever is released by the cam and the locking bar is urged back by its spring into a position 50 in which it will be engaged by a conical or cam inner end of the pin 30 during a later stage of the closing of the flap.

55 The stop on the flap will have been withdrawn from 60 operative position during the opening of the flap, the locking pawl then retaining the holder against rotation.

The said stop and the locking pawl are relatively positioned so that when the stop was withdrawn from the holder during the opening of the flap and after the pawl has reached the position shown in FIG. 2, the holder would have turned slightly to enable the vertical rod which previously co-operated with the stop to move on out of co-operation therewith. The said stop will thus during the closing of the door be positioned ready to receive the next vertical rod when the holder is again released 65 by the locking pawl and turns.

70 During further closure of the flap, the conical or cam end of the bolt will press the locking bolt against its spring until, when the flap is nearly closed, the end of the locking bolt will snap into the groove in the pin 30.

75 Some slight further closing movement of the flap is

then permitted and it is only after this entry of the end of the bar into the groove, or substantially simultaneously therewith, that the lower extension of the flap will apply the necessary pressure on the master lever to cause this through the intermediate lever to displace the locking pawl against its spring and release the holder for turning. The angular extent of turning of the holder will now be determined by the stop on the flap and the apparatus is ready for the next cycle of operations, after the holder has again come to a standstill, and following the insertion of another coin.

If two coins are inserted one immediately following the other, the second coin will be held back by the horizontal plate 44 on the locking bar and prevented from falling until the bar has been again retracted and the previous coin discharged and the second coin allowed to come to rest on the pins and be held between the plate on the locking bar and that carrying the pins.

Referring to the machine shown in FIGS. 6 to 11 the cabinet 101 has a hinged door 102, the cabinet having a closed top 103 which may bear indicia of any suitable sort and a lower door or closure panel 104 which can be opened or removed to facilitate cleaning of the machine. The holder 105 is divided into sectorial compartments 105a, the outer edges of the partitions 106a forming a rack 106 with which co-operates a spring loaded pawl 107 mounted on a bracket 109 in the cabinet.

A closure member 110 adapted when open to expose one compartment only of the holder is pivoted by horizontal journals 111 on the door. The opening covered by the closure member is formed in a rectangular recess in the door and is framed by a surround including a curved top 112 and side walls 113. The closure member carries a pin 114 with an external finger knob 115, a peripheral groove 116 where it projects within the door and a conical leading end 117. When closing the door the conical end of the pin engages a conical socket 118 in a plunger 119 housed in a block 119a secured to the door, the plunger 119 being loaded by a spring 120 and this spring is compressed. The end 121 of the locking bolt 122 then engages the peripheral groove.

A coin is inserted from the exterior of the machine into a coin receiving mechanism 123 and if the correct coin has been inserted it passes down a chute 124 and comes to rest edgewise supported by pins 125 projecting from a plate 126 fixed to the door 102. The coin is retained on these pins by a plate or flange 127 projecting from and attached to the locking bolt. The plate 126 and the plate or flange 127 on the bolt are holed at 128, 128a to allow for passage of the pin 129 on the externally operable manual control lever 130 save when a coin has been inserted and is held by the pins 125 when operation of said control lever 130 releases the bolt from the pin 114 allowing the spring plunger to urge the closure member into open position. Plate 126 is part of a bracket 126a which is secured to the door and which comprises another plate 126c between which and the plate or flange 127 attached to the bolt a compression spring 126c is situated which serves to return the bolt to locking position. The line 126d (FIG. 9) denotes the right-hand extremity of the bracket 126a and the bolt is slidably in a horizontal slot in the bracket.

During opening of the closure member the tail extension 131 of the member disengages the lower arm 132a of a master lever 132 and allows the master lever 132 to pivot in the bracket 133 attached to the door 102 under the action of spring 132b thus withdrawing the adjustable screw pin 134 on the master lever 132 from its normal engagement with the end 107a of pawl 107 and allowing the pawl to be spring-urged about its pivot 107b into the path of the holder. Subsequently a stop 135 on the closure member withdraws from its normal engagement with the rack 106 (shown in dotted outline in FIG. 7) and releases the holder which turns to the

dotted position A (FIG. 7) to abut the said pawl and pass the said stop position.

When the goods have been withdrawn from the exposed compartment the closure member is closed and the stop 135 is again introduced into the path of the holder. When the closure member is nearly closed a quadrant 136 which turns therewith (in an anti-clockwise direction in the aspect of FIG. 8) is engaged by a spring-loaded pawl 137 to prevent the closure member from being re-opened. During movement of the closure member to closure position the tail 131 of the closure member engages the lower arm 132a of the master lever 132 and causes this lever to pivot in the bracket 133 against the pressure of its spring 132b so that the adjustable screw pin 134 on lever 132 engages the end 107a of pawl 107 and, during final closure movement of the closure member, withdraws the pawl 107 from the holder rack 106 so that the holder can turn until arrested by the stop 135 on the closure member. Also during the said final closure movement of the closure member the quadrant 136 rides past the pawl 137. When the closure member is released for opening the quadrant 136 can ride past the pawl 137 without locking with it.

An "empty" sign 141 (FIGS. 10 and 10a) is provided in the last compartment in the holder, this sign being hinged connected at 142 to the floor of the compartment and normally being held in a raised, out-of-sight position, by the cam 140 on the slide 139. A pin 138 on the slide 139 projects through an aperture in that part of the side wall of the last compartment which will be contacted by the stop 135 on the closure member when the holder 106 makes its last turning movement. Thus when the last compartment containing goods has been emptied and the closure member closed the holder 106 will turn until arrested by the stop 135 on the closure member. When the holder is arrested by the stop 135 the pin 138 will be moved towards the right in the aspect of FIG. 10 and move the cam 140, carried by the slide 139, from under the empty sign so that this can hinge down under its own weight into a position in which it will be exhibited through a window in the closure member.

The coin receiving mechanism is designed to take coins of two values and of different diameter (e.g., the English florin and half-crown) and to reject coins of the wrong diameter and or thickness. It comprises a track 143 for the coin formed by the inturned flange of a plate 144 hinged at 145. A diameter control plate 146 is adjustable by means of screws 147 in relation to a fixed mounting plate 148 according to the diameter of the coin. It provides a channel 149 just sufficient to take the thickness of the coin. The coin is entered through a slot 151 in the front of the door. A coin larger than that for which the plate is set will merely lodge against the edge 150 of the said plate 146. A coin thinner than the prescribed coil will fall through a slot 152 in the track 143, the slot being of unsufficient width to prevent the support of the proper coin. A coin of smaller diameter than that for which the plate 146 is set, i.e., a florin when the plate 146 is set for half-a-crown, will not engage the channel 149 but will tilt over and project into a locking aperture (not shown) in the fixed plate 148 and will thus be held in the coin receiving mechanism and prevented from running down into the chute. The rejected coin passes down chute 153 to a coin reject cup 154. The hinged plate 144, hinged at 145 and apertured at 144a thus exposing plate 146 (FIG. 11), can be opened for the release of a coin trapped by the said edge 150 or by the said aperture in the fixed plate 148 by pushing on the spring loaded externally accessible knob 155 which co-operates with a cam face 156 on the hinged plate. The then rejected coin runs down the coin chute 153 to the coin-reject cup. The passed coin runs down the chute 124 and lodges on the pins 125 on the plate 126 and is finally released down chute 159 for passage into an in-

terior coin receiving box 160 which may have a hinge-up cover 161 that can be locked if desired.

163 indicates a locking mechanism for the door. 163a is a magnet carried by the hinged plate and projecting through holes in the said plate and the plate 146 to hold back a spurious coin of ferromagnetic material.

The machine is simple in construction, relatively cheap to make and fool proof and tamper proof in use. It may have a large capacity for the goods to be sold and can handle goods of awkward shapes or goods in awkward shaped packages, it may, for example, be used for goods wrapped in paper bags or for goods such as eggs in special containers therefor. The machine may accept coins of different denominations and deliver change with the goods and may be completely mechanical in operation so that it can be installed where no electricity supply is available. Moreover, the machine may be refrigerated where it is used to handle food stuffs or it may deliver goods directly from a deep freeze compartment.

If desired, whilst the closure member remains open, the coin slot into which money is inserted, may be closed so that coins cannot be inserted into the machine. Alternatively, the coin receiving mechanism may be arranged so that if a coin is inserted into the machine whilst the closure member remains open, then the coin is returned to a rejected coins delivery cup. If the goods in the compartment are to be sold for less than the value of the coin which is inserted in the slot, then the change which is to be delivered to the customer may be contained in the goods compartment or may be packed with the goods.

What I claim is:

1. A vending machine comprising a holder for the goods to be vended having a number of compartments to contain the goods, a casing for said holder having an access opening and a closure member therefor, the holder being supported to move downward in a helical path by gravity in said casing to bring each compartment in turn into register with said opening, said closure member being a member pivoted to the casing and providing when closed a stop for the said holder, means operative when a coin is in a position to serve as a link or coupling to unlock or unlock and open the said closure member, indexing means operative when the closure member opens to intrude into the path of the holder and to retain the holder when the said stop on the closure member has been withdrawn, said last-mentioned means being operative by closing the closure member to release the holder to turn by gravity up to the said stop on the closure member and bring another compartment to the said opening.

2. A vending machine comprising a holder means for the goods to be vended having a number of compartments to contain the goods, a casing for said holder having an access opening and a closure member therefor, means in said casing supporting said holder, said supporting means comprising an axial column, said holder being supported to move in a helical path about said supporting means to bring each compartment in turn into register with said opening, said helical path being defined by a helical arrangement of pins on said column and a local helical surface on the said holder and means operative when a coin is in a position to serve as a link or coupling element to unlock or unlock and open said closure member, means controlled by the closure member to allow the holder to advance to bring another compartment to the opening.

3. A vending machine according to claim 2 in which said helical surface extends over less than 360° and is formed by the central edge of a sleeve secured to the lower part of the said holder.

4. A vending machine according to claim 2 in which said pins are screwed into the said column and tend to be tightened by the descent of the holder thereon.

5. A vending machine according to claim 1 comprising a coin track means, means to support a coin in a predetermined position, a locking bolt for said closure member,

an operating control operable from the exterior of the machine for displacing said bolt to unlock the closure member, the arrangement being such that when the coin is in such position motion will be transmitted from said control to the said bolt but not when a coin is not in such position.

6. A vending machine according to claim 5 in which the initial opening of the closure member is limited by cam means on the closure member co-operating with lever means which co-operate with the locking bolt to prevent premature return of the bolt and so that the further opening of the closure member further displaces the bolt.

7. A vending machine according to claim 5 in which the closure member has a grooved pin with which the said bolt locks, the pin co-operating with a spring-loaded plunger which serves to hold the bolt ready to engage the pin whilst the closure member is open and yields to the pin when the closure member is partaking of its final closing movement to enable the bolt to come into operative position and which causes the closure member automatically to open when released by the locking bolt.

8. A vending machine according to claim 1, in which the holder comprises vertical members which together form a rack and the indexing means comprise a catch normally released from the said rack when the closure member is closed, said stop co-operating when the closure member is closed with the said rack to register a compartment with said opening, said indexing means being responsive to initial opening of the closure member to cause the catch to move into position to co-operate with said rack and so that by further opening of the closure member to release the said stop means from the rack the holder can turn a small angular extent to engage the catch and bring the rack into a position in which the holder, when next released by the catch can turn until the next vertical member of the rack is held by the stop means of the then closed closure member, and comprising a biasing means responsive to the unlocking and opening of the closure member which cause opening of the latter member at least sufficient to bring the catch into operative position.

9. A vending machine according to claim 8, comprising means whereby the operation of the catch to release the holder for rotation occurs only by the final movement of the closure member when the locking bolt has again caught the closure member and retained the closure member against improper opening.

10. A vending machine according to claim 1 comprising a toothed quadrant and pawl device responsive to closing movement of the closure member to prevent opening of the latter when this has been nearly closed and before the holder is released for turning.

11. A vending machine according to claim 1, in which the holder is within a casing comprising a door which can be normally locked or opened for charging the holder and the said opening is in the door and the said closure member is a fold-down flap pivoted to the door, said door comprising means to support a coin in a predetermined position, a locking bolt for said closure member and an operating control operable when a coin is present from the exterior of the door when closed for displacing said bolt to unlock the closure member, said holder comprising vertical members which together form a rack and said indexing means comprising said stop and a catch, said stop being withdrawable from the said rack when the closure member is opened and said catch then permitting a small angular movement of the holder, said catch operating to prevent movement of the holder while the closure member is open and means for causing the closure member when nearly closed from again being re-opened, and said catch being releasable by the closure member only when said means to prevent re-opening of the closure member are effective.

12. A vending machine according to claim 1, in which

11

the holder is within a casing comprising a door which can be normally locked or opened for charging the holder and the said opening is in the door and the said closure member is a flap pivoted to the door, said holder comprising vertical members which together form a rack and a pawl mounted on the interior of the said casing and co-operating with the said rack, said holder being adapted to be turned and raised when the door is opened and said

12

pawl then co-operating with the rack to prevent reverse turning movement and descent of the holder.
